UNITED STATES PATENT OFFICE.

WILLIAM W. ROACH, OF PHILADELPHIA, PENNSYLVANIA, ASSIGNOR OF SIX ONE-HUNDREDTHS TO EDWARD A. TEEPELL, OF WEST PHILADELPHIA, PENNSYLVANIA, AND ONE-THIRD TO HARRY J. WARING, OF NEW YORK, N. Y.

AUTOMOBILE-BRAKE.

14,426.

Specification of Reissued Letters Patent. Reissued Jan. 22, 1918.

Original No. 1,171,655, dated February 15, 1916, Serial No. 28,061, filed May 19, 1915. Application for reissue filed April 22, 1916. Serial No. 38,036.

To all whom it may concern:

Be it known that I, WILLIAM W. ROACH, a citizen of the United States, residing at Philadelphia, in the county of Philadelphia, State of Pennsylvania, have invented a new and useful Improvement in Automobile-Brakes, of which the following is a full, clear, and exact description, reference being had to the accompanying drawings, which

10 form a part of this specification.

The object of my invention is to effectively apply a braking action to an automobile wheel or to any other wheeled vehicle by bringing a disk rotating with the wheel into frictional contact with one or more non-rotating plates and preferably with one or both of two pairs of concentric annular plates connected respectively to the devices adapted for independent actuation by the

20 hand and by the foot.

A preferred embodiment of the invention is shown in the accompanying drawings, in which—

Figure 1 is a face view of the apparatus showing more especially the devices for operating both sets of brake-plates. Fig. 2 is a section on the line 2—2 of Fig. 1. Fig. 3 is a section looking in the direction of the arrow 3—3 of Fig. 2. Fig. 4 is a section on the line 4—4 of Fig. 1, showing the hand-actuated device for frictionally applying the inner pair of friction plates. Fig. 5 is a view looking in the direction of the arrow 5—5 of Fig. 1, showing the foot-operated device for frictionally applying the outer pair of friction plates. Fig. 6 is a perspective view of two of the slides (connected to one pair of friction plates) which are operated by one of the actuating devices above named. Fig. 7 is a perspective view of one of the wedge sections of one of the actuating devices.

Within the axle tube *a* is the axle *b* to which is secured the wheel, one edge of the wheel spokes being indicated by the line *c* of Fig. 2. To the wheel *c* is secured brackets *d* carrying an annular disk *e*. Inside brackets *d* are two annular plates *f*, *f*, on opposite sides of disk *e*. These plates may

be faced with a suitable friction material *f*. Outside brackets *d* are two annular plates *g* on opposite sides of disk *e*. These plates may also be faced with a suitable friction material.

To axle tubes *a* is secured a plate *h* having two sets of tubular pockets extending parallel to the axle. One set of tubes *m* receives sliding members which connect with friction plates *f*, *f*. The other set of tubes *n* receives sliding members connected with friction plates *g*, *g*. Thus, to the friction plate *f* nearest the fixed plate *h* is secured a bracket *i* supporting a semi-circular slide *i* extending into the tube *m*. To the friction plate *f* on the other side of disk *e* is secured a bracket *j* carrying a slide *j* extending into the tube alongside slide *i* and being, throughout this part of its length, of semi-circular cross-section, but extending beyond slide *i* and having an end or head of circular cross-section which is spaced from slide *i* to receive a wedge hereinafter described. The end of tube *m* is closed by a threaded plug *o*. A spring *p*, confined between plug *o* and head of slide *j*, tends to maintain the more distant plate *f* spaced from disk *e*. The other set of tubes *n* receives similar slides *k* and *l* which are simultaneously connected to the two plates *g*, *g*. These tubes have also threaded plugs *o* and springs *p*.

There is a wedge *r* for each tube *m* and a wedge *v* for each tube *n*. The set of wedges *r* is carried on the inside of a turnable ring *s* to which is secured an arm *t* which, through suitable connections, may be operated manually (preferably by hand) to turn ring *s* so as to cause each wedge *r* to pass between the end of a slide *i* and the head of corresponding slide *j*, thereby causing the slides to move in opposite directions and applying both plates *f*, *f* to the disk *e*.

The set of wedges *v* is carried on the outside of a turnable ring *w* to which is secured an arm *x* which, through suitable connections, may be operated manually (preferably by foot) to turn ring *w* so as to cause each wedge *v* to pass between the end of a

slide *k* and the head of corresponding slide *l*, thereby causing the slides to move in opposite directions and applying both plates *g*, *g* to the disk *e*. Leaf springs *y* may be arranged between the plates *f*, *g* on one side of disk *e* and the plates *f*, *g* on the other side of disk *e* thereby holding all the plates out of contact with the disk.

The described construction, which may be modified in detail without departing from my invention, is not expensive to construct, occupies a small amount of space, affords a great area of brake surface, and operates with ease, smoothness, certainty and power.

Having now fully described my invention, what I claim and desire to protect by Letters Patent is:—

1. A disk brake comprising a friction disk turning with the wheel, a pair of annular friction plates, said plates arranged on opposite sides of the disk, a fixed plate and a number of pockets carried thereby, slides secured to the nearer friction plate and extending into said pockets, slides secured to 25 the more distant friction plate and extending into said pockets and beyond the other slides, wedges each extending between a pair of slides in one of the pockets, and a manually operable turnable device carrying said 30 wedges.

2. A disk brake comprising a friction disk turning with the wheel, a pair of annular friction plates, said plates arranged on opposite sides of the disk, a series of pairs of slides secured to the respective plates, a turnable ring, a series of wedges carried on one face of the ring and movable between the slides of the respective pairs, and an arm for operating the ring.

3. A disk brake comprising a friction disk turning with the wheel, two pairs of annular friction plates located at different distances from the wheel's axis, the two plates of each pair located on opposite sides of the disk, and means to simultaneously move the two plates of each pair toward each other against opposite faces of the disk.

4. A disk brake comprising a wheel, a friction disk, brackets secured to the wheel and supporting the disk, two annular friction brakes on opposite sides of the disk outside said brackets, two annular friction brakes on opposite sides of the disk inside said brackets, means to simultaneously move the outside plates toward each other against the disk, and independent means to simultaneously move the inside plates toward each other against the disk.

5. A disk brake comprising a friction disk turning with the wheel, two pairs of annular friction plates located at different distances from the wheel's axis, the two plates of each pair located on opposite sides of the disk, a series of pairs of slides secured to the respective plates of each pair, two turnable

rings, a series of wedges carried on one face of one ring and movable between the slides of the respective pairs of slides of one series, a series of wedges carried on one face of the other ring and movable between the 70 slides of the respective pairs of the other series, and independently operable arms for operating the respective rings.

6. A disk brake comprising an axle tube, a fixed plate secured thereto, an axle within 75 the tube, a wheel secured to the axle, pockets secured to said plate and extending parallel to the wheel's axis, a disk in fixed relation with the wheel, friction plates on opposite sides of the disk, slides secured to said plates 80 and extending into said tubular pockets, turnable arms, and wedges carried thereby extending into said pockets and adapted, when turned with their arms, to cause the slides to move in opposite directions and 85 thereby frictionally apply the friction plates to the disk.

7. A disk brake comprising a member having pockets, a disk turning with the wheel, friction plates on opposite sides 90 thereof, pairs of slides connected to the plates, the two slides of each pair connected to opposite plates and entering a pocket, manually operable wedges each adapted to engage the two slides of a pair and move 95 their corresponding plates toward each other against the disk, threaded plugs closing the pockets, and a spring confined in each pocket between the plug and one of the slides.

8. A brake comprising a friction disk rotating with the wheel, two non-rotatable friction elements of different diameters, and means for arbitrarily actuating either of said non-rotatable friction elements, independently of the other, into braking engagement with the rotatable disk.

9. A brake comprising two pairs of non-rotatable friction elements, of different diameters, a friction disk turning with the 110 wheel interposed between the two elements of each of said pairs, and means for arbitrarily actuating either of said pairs independently of the other into braking engagement with said rotatable disk.

10. A double friction brake for motor vehicles and the like, comprising the combination with the fixed rear axle, the driving shaft therein, and the wheel connected to said shaft, of a friction disk rigidly secured 120 to said wheel, independent pairs of friction rings secured to said axle on each side of said disk, and independent, manually operable means for forcing said rings into engagement with said disk.

11. A brake for motor vehicles comprising a friction disk, connections between the same and the wheel to be braked such that said disk rotates with the wheel, two pairs of non-rotatable friction rings flanking said 130

disk one outside the other, and independent means to actuate each pair of rings to retard said disk.

12. A brake for a shaft, comprising a friction disk rotatable with the shaft, two non-rotatable friction rings, one within the other, on one side of said shaft, two similar

rings on the other side of said shaft, means to cause the pair of larger rings to engage said disk and independent means to cause the pair of smaller rings to engage the same.

WILLIAM W. ROACH.
